Des. 202,807
Patented Nov. 9, 1965

202,807

FLUORESCENT LIGHT FIXTURE

Gertrude Preston, London, England, assignor to Preston Industrial Research Limited, London, England, a British corporation

Filed June 1, 1964, Ser. No. 80,226

Claims priority, application Great Britain Mar. 31, 1964

Term of patent 14 years

(Cl. D48—23)

Fig.3

FIG. 1 is a perspective view of a fluorescent light fixture showing my new design;

FIG. 2 is an elevation thereof; and

FIG. 3 is a bottom plan view thereof.

The dominant features of my design reside in the portions shown in full lines.

I claim:

The ornamental design for a fluorescent light fixture, as shown and described.
